ATTORNEY.

UNITED STATES PATENT OFFICE.

LOUIS C. PARKER, OF VALE SUMMIT, MARYLAND, ASSIGNOR OF ONE-HALF TO WILLIAM A. PARKER, OF PITTSBURGH, PENNSYLVANIA.

RAILROAD-TIE.

1,016,517.

Specification of Letters Patent.

Patented Feb. 6, 1912.

Application filed April 27, 1911. Serial No. 623,622.

To all whom it may concern:

Be it known that I, LOUIS C. PARKER, a resident of Vale Summit, in the county of Allegany and State of Maryland, have invented a new and useful Improvement in Railroad-Ties, of which the following is a specification.

My invention relates to structures for supporting and fastening rails used in railroad construction, and also to means for insulating the rails from their supporting and fastening structures when they are utilized as conductors of electric currents for operating signals or for other purposes.

15 The object of my invention is to provide a rail-supporting tie of special construction and coöperating rail fastening devices of simple and durable construction that may be readily applied and as readily detached or removed when it is desired to replace a rail and that may also be relatively adjusted to accommodate rails of different sizes when it is desired to effect a lateral adjustment of a rail upon the tie.

20 25 A further object of my invention is to provide a simple readily applied and effective means for insulating a rail from its supporting and fastening structure.

In the accompanying drawings, Figure 1 is a plan view of a portion of a rail and a portion of a tie equipped with rail fastening and insulating devices in accordance with my invention; Fig. 2 is an end elevation and Fig. 3 a plan view of one of the fastening 30 35 wedges; Fig. 4 is a side elevation of a portion of the tie and the rail fastening and insulating devices, the rail being shown in cross section and a portion of one insulating plate being broken away; Fig. 5 is a view at right angles to Fig. 4, showing the tie in cross section and the rail fastening and insulating devices in elevation; Figs. 6 and 7 are diagrammatic plan views illustrating two arrangements of rail-receiving recesses 40 45 for adjacent ties.

In order to properly support the rails, I provide transversely disposed ties at frequent intervals, in accordance with the usual practice, but, according to the present invention, I utilize ties having certain new structural characteristics and employ, in conjunction therewith, special insulating and rail fastening devices which will be hereinafter more fully described.

As shown in the drawing, I employ metal, 55 preferably steel ties 2 that are severally of substantially I-beam form and provided with a longitudinal rib 3 on its upper surface, said rib being preferably integral with the body of the tie and at suitable intervals 60 provided with spaces or notches 4 to receive the rails 1, the ribs being cut away in order to provide such spaces or notches. The rib at each side of each space or notch 4 is overhanging, and the inner face of the overhanging 65 portion 5 is inclined downwardly and outwardly to a line 6 and, from the line 6 to the vertical inner side 6^a of the space, it is inclined upwardly, as is clearly indicated in Fig. 4. The inner face of the overhanging 70 portion or lip 5 of the rib 3 is beveled with reference to a horizontal plane, and the boundary lines of this beveled face and also the vertical end wall 6^a are in parallel vertical planes that make acute angles with the 75 rail 1 in order to conform to corresponding beveled and inclined portions of a wedge 10.

The wedge 10 is under-cut at the side next to the rail 1 and is provided with an inner face 11 which is inclined to the horizontal 80 at such an angle as to conform substantially to the inclined upper surface of the base flange 12 of the rail 1. The wedge 10 is also provided with a hole 10^a which extends through it from side to side to receive a bolt 85 13, one end of which is bent at 14 to engage one edge of the top flange of the tie 2 and the other end of which is provided with a screw thread to receive a nut 15.

It will of course be understood that each 90 rail-receiving space or notch 4 has overhanging side walls or lips that are substantially alike in form and dimensions, and that a wedge like that described is utilized at each side of the rail in conjunction with the corresponding overhanging rail space wall or lip.

In order to properly insulate the rail 1 from the wedges 10 and the tie 2 I provide two plates 16 each of which is composed of a sheet 100 of hard vulcanized fiber 17 or other suitable insulating material and two protective metal sheets 18. The plates 16 fit beneath the base flange 12 of the rail 1 within the space 4 and have their ends bent downwardly over the 105 edges of the tie 2, as indicated at 19. Portions of the outer edges of the plates 16 are extended and bent upwardly and inwardly

to fit over the edges of the base flange 12 of the rail 1 and between the same and the adjacent inner faces 11 or wedges 10.

As indicated in the figures hereinbefore considered, the tie is of rolled steel I-beam form and is provided with an integral longitudinal rib on its upper surface which extends from end to end of the tie except as it is cut away to form spaces for the rails, 10 and, in order to facilitate the cutting away to form the spaces at a single operation, I have indicated the corresponding lines of the opposite side walls of the rail spaces as parallel to each other, this construction also 15 making it feasible to use interchangeable wedges for fastening the rail to the tie. It will be understood, however, that the top projections for coöperating with the fastening wedges may, or may not, extend from 20 end to end of the tie, except as spaces are provided for the rail, though when the rib constitutes an integral part of a rolled metal tie it will naturally and properly be uninterrupted, except at the rail spaces. It will 25 also be understood that the cross-sectional form of the tie may be different from what I have shown and that my invention is not limited to the employment of ties having integral ribs or projections or to ties formed 30 of any specific material or materials.

In Fig. 6 I have shown diagrammatically two rails 1 and two supporting ties 2 for the purpose of indicating that corresponding lines of all rail space walls and wedges are 35 parallel. By employing this arrangement, I am enabled to use a single form of wedge 10.

In Fig. 7 I have indicated diagrammatically the possibility of opposing the wedges 40 of adjacent ties to each other by inclining the corresponding wall lines of adjacent rail spaces in different directions, it being observed that the lines of the walls of the spaces 20 and 21 of the tie 22 project in 45 different directions and that the lines of the walls of the spaces 23 and 24 of the tie 23 also project in different directions, the lines of the spaces 20 and 24 being parallel and the lines of the spaces 21 50 and 23 being also parallel, but it is not to be understood that I regard this arrangement as necessarily preferable to the arrangement in which corresponding lines of the walls of all rail spaces are in parallel 55 relation, as shown in Fig. 6. It will of course be understood that, with the arrangement shown in Fig. 7 it will be necessary to employ right hand and left hand wedges, and that such arrangement will insure opposite wedging effects for adjacent ties.

Whatever be the arrangement adopted in practice, as regards the rail spaces and the form and the material of the tie, it will be observed that the rails will be effectively insulated and securely fastened in position and

that the rails may be released readily by merely removing the nuts 15 from the bolts 13 and exerting a slight degree of pressure or a blow upon the narrow ends of the wedges.

What I claim is:

1. A rail supporting and fastening structure comprising a tie having on its upper surface projections spaced apart to receive a rail, each of said projections being undercut to form a recess the rear wall of which is at an angle to the central vertical plane of the rail to be clamped, and the underfaces of the overhanging projections being inclined upwardly in the direction toward the rail and also being at an angle to the central vertical plane of the rail, and a wedge adapted to be inserted in each of said recesses, said wedge at its inner edge having a shoulder adapted to engage the edge of the rail base and an inclined lip adapted to overhang the rail base, and having its outer edge tapered to engage the rear wall of the recess and its top surface tapered on an angle to the central vertical 90 plane of the rail, whereby when said wedge is forced into said recess it exerts a pressure inwardly against the edge of the base of the rail and downwardly against the top face of the base of the rail. 95

2. A rail supporting and fastening structure comprising a tie having on its upper surface projections spaced apart to receive a rail, each of said projections being undercut to form a recess the rear wall of which is at an angle to the central vertical plane of the rail to be clamped, and the underface of the overhanging projections being inclined upwardly in the direction toward the rail and also being at an angle to the central vertical plane of the rail, and a pair of wedges adapted to be oppositely inserted in said recesses, each wedge at its inner edge having a shoulder adapted to engage the edge of the rail base and an inclined lip adapted to overhang the rail base, and having its outer edge tapered to engage the rear wall of the recess and its top surface tapered on an angle to the central vertical plane of the rail, whereby when said wedges are forced into said recesses they exert a pressure inwardly against the edge of the base of the rail and downwardly against the top face of the base of the rail. 105 110 115

3. A rail supporting and fastening structure comprising a tie having a rib projecting from its upper surface and being cut away at intervals to provide rail receiving spaces having overhanging projections, the rear walls of the spaces being vertical and at an angle to the central vertical plane of the rail to be clamped and the underfaces of the overhanging projections being inclined with reference to the horizontal plane and being beveled with reference to the ver- 120 125 130

- tical central plane of the rail to be clamped, and a pair of wedges adapted to fit the walls of the undercut rail receiving spaces and each provided at its inner edge with a shoulder adapted to abut against the edge of the rail base and with a beveled lip overhanging the rail base, whereby when said wedges are forced into said rail receiving spaces they provide inward and downward pressure against the base of the rail.
4. A rail-supporting and fastening structure comprising a tie provided with overhanging top projections spaced apart to receive a rail between them and having beveled inner faces, bevel faced wedges interposed between the base flange of a rail and said bevel faces, metal faced insulating plates interposed between the rail flanges and the tie and between said flanges and the wedges, and locking devices for the wedges.
5. A rail-supporting and fastening structure comprising a tie having a top rib cut away to form a rail-receiving space having overhanging sides, the inner faces of which are beveled and substantially parallel, insulating plates having downwardly turned ends to engage the edges of the tie and upwardly and inwardly turned sides to fit around the edges of the base flanges of a rail, wedges adapted to fit between the insulating plates and the overhanging sides of said rail-receiving space, and means for fastening the wedges in their locking positions.
6. A rail supporting and fastening structure comprising a metallic tie, a pair of insulating plates fitting over the base flanges of the rail and extending underneath the same, each of said plates comprising a sheet of insulation and a metal plate on each face thereof, and means for securing a rail and said plates to the tie.
7. A rail supporting and fastening structure comprising a metallic tie, a pair of insulating plates therefor each comprising a sheet of insulation and a metal plate on each face thereof, said plates adapted to lie between the rail base and the tie and provided with upturned portions engaging and overhanging the rail base flanges and with down-turned end portions engaging the edges of the tie, and means for securing a rail and said insulating plates to the tie.
8. A rail supporting and fastening structure comprising a tie having on its upper surface projections spaced apart to receive a rail, each of said projections being undercut to form a recess the rear wall of which is vertical and at an angle to the central vertical plane of the rail to be clamped, and the under face of the overhanging projection being inclined in the direction toward the rail first downwardly and then upwardly and also being at an angle to the central vertical plane of the rail, and a wedge adapted to be inserted in each of said recesses, said wedge at its inner edge having a shoulder adapted to engage the edge of the rail base and an inclined lip adapted to overhang the rail base, and having its outer edge tapered to engage the rear wall of the recess and having its top surface inclined and tapered on an angle to the central vertical plane of the rail to fit the under face of the overhanging projection, whereby when said wedge is forced into said recess it exerts a pressure inwardly against the edge of the base of the rail and downwardly against the top face of the base of the rail.
9. A rail tie comprising a body provided with a longitudinal rib on its upper surface, said rib being transversely notched to provide overhanging beveled lips, rail fasteners provided with beveled bodies for wedging engagement with said lips and with rail-engaging means, said bodies being provided with holes, and bolts located in said holes and provided with hooks to engage the tie and with nuts to engage said bodies.

In testimony whereof, I have hereunto set my hand.
